UNITED STATES PATENT OFFICE.

ANTONI BULINSKI, OF ABERDEEN, WASHINGTON.

MARINE TABLE.

Application filed September 29, 1920. Serial No. 413,473.

To all whom it may concern:

Be it known that I, ANTONI BULINSKI, a citizen of the United States, residing at Aberdeen, in the county of Grays Harbor 5 and State of Washington, have invented certain new and useful Improvements in a Marine Table; and I do hereby declare the following to be a full, clear, and exact description of the invention, such as will enable others skilled in the art to which it appertains to make and use the same.

The object of the invention is to provide simple and efficient means for maintaining a table top in a condition of horizontality 15 regardless of vibrations and oscillations of the support or base of the same, and more especially to provide a table which is adapted for use on ship-board, wherein the top is maintained in a proper position to hold 20 and sustain the objects imposed thereon regardless of the rolling or pitching of the vessel, and in connection with the gravitational leveling means provided for the table to employ means serving to prevent a pen- 25 dulous or prolonged swinging movement of the table top; and with this object in view the invention consists in a construction and combination of parts of which a preferred embodiment is shown in the drawings, 30 wherein:

Figure 1 is a side view partly in section of a table embodying the invention.

Figure 2 is a horizontal section on the plane indicated by the line 2—2 of Figure 1.

Figure 3 is a detail view of the ring forming one element of the universal mounting,

Figure 4 is a detail section of a portion of one of the equalizing devices.

Figures 5 and 6 are elevations from different sides of a modified construction of the table.

In the construction illustrated in Figures 1 to 4 inclusive the table top 10 is carried by a weighted stem 11 which is universally mounted upon a frame including the supporting disk 12 and the legs or standards 13 which may be transversely connected by a suitable brace 14. The stem 11 is provided at its lower end with a weight 15 of sufficient weight to insure stability and avoid vibration except under conditions involving unusual movement of the supporting vessel, said stem having a ball 16 provided with trunnions 17 which are mounted in seats 18 50 in a ring 19 which in turn is provided with trunnions 20 disposed in a plane at right

angle to that of the trunnions 18 and are mounted in bearings in the disk 12, to the end that the weight 15 is adapted to maintain the stem 11 in a truly vertical position 60 and hence the table top 10 in a horizontal position regardless of movement of the supporting frame consisting of the disk 12 and legs or standards 13 of which the lower ends of the latter are preferably secured as by 65 screws or bolts 21 to the vessel deck or floor. The weight is secured upon the stem 11 by means of a nut 22 or the equivalent thereof, and the attaching plate 23 at the upper end of the stem is preferably integral therewith 70 and is secured by screws 24 to the under surface of the table top.

Disposed at intervals in a series concentric with the stem 11 or the axial center of the supporting frame are the equalizing devices 75 consisting in the construction shown in Figures 1 and 4 of cylinders or dash pots 25 in which operate pistons 26 of which the rods 27 are pivotally connected as at 28 to the under surface of the table top, the lower 80 ends of the cylinders or dash pots being universally mounted as by ball and socket joints 29 upon the legs or standards of the frame work and being provided with vents 30 fitted with regulating valves 31 to modify the freedom of the passage of air through the vents 85 due to the downward and upward movement of the pistons incidental to the movement of the supporting frame with relation to the horizontally maintained table top 10. These 90 equalizing means of which a plurality should be provided with each apparatus, tend to relieve the jars incident to the sudden movements of the supporting frame with relation to the table top and permit the latter to be 95 maintained in a substantially uniform horizontal position without the vibration or swinging movement which would be incidental otherwise to the impulses imparted to the counter-balancing weight 15 by the sudden changes in the direction of movement of the vessel or other support to which the legs or standards are attached.

In the modified construction illustrated in Figures 5 and 6 the table top 32 is attached 105 to a plate 33 at the upper end of a stem 34 also having a counter-balancing weight 34 and a ball 36 which is mounted in a spherical socket 37 supported by or forming a part of the disk 38 upheld by the legs or standards 39 which are braced as indicated at 110 40. The stem with its bearing ball 36 and

attaching plate 33 is preferably of single piece construction, as in the form illustrated in Figure 1, and the equalizing devices employed in connection with the form shown 5 in Figures 5 and 6 consists of bars 41 supported by cushioning springs 42 and traversed by wings 43 depending from the table top and having a pivotal or rocking mounting thereon as shown at 44, the intermediate portions of said wings forming runners 45 having a tongue and groove engagement with the bars 41 so as to compensate for the angular relative movement in any direction of the table top and supporting 10 15 frame and serve to prevent the swinging or prolonged vibratory movement of the table top due to the movement of the surface by which the frame of the structure is supported.

Having thus described the invention, what I claim is:

In a table, a top, means supporting said top for substantially universal movement including legs extending upwardly and inwardly, a pendulum for said top, equalizing supports connected to said top at a distance from the axis thereof and to said legs at a distance above the bases of said legs, and said supports being disposed respectively in planes passing intermediate the terminals of the legs supporting them.

In testimony whereof I affix my signature in presence of two witnesses.

ANTONI BULINSKI.

Witnesses:

W. W. WILEY,
H. W. GIBSON.
